DISPLAY APPARATUS.

Application filed December 31, 1926. Serial No. 158,202.

The present invention relates to an improvement in display apparatus.

The object of the invention is to produce an apparatus for use in displaying commodities by exhibiting them in motion in a show window or otherwise, and to this end the invention consists in the apparatus hereinafter described and particularly defined in the claims.

In the accompanying drawings illustrating the preferred form of the invention, Fig. 1 is a plan view of the apparatus; Fig. 2 is a front elevation of the same; Fig. 3 is an enlarged plan similar to that shown in Fig. 1, showing only part of the apparatus, but showing the position of some of the hidden parts in dotted lines; Fig. 4 is a bottom view of the gear box; Fig. 5 is a section taken on the line 5—5, Fig. 3, showing the gearing in front elevation; and Fig. 6 is a transverse section of the mechanism taken on the line 6—6, Fig. 3.

The illustrated embodiment of the invention is described as follows: The apparatus is provided with a table 10 supported by a box 11. On top of the table is supported the carrier for carrying different devices desired to be exhibited. A carrier chain 12 is supported on top of the table 10, and held in rectangular position by the carrier guide 13. This guide is shown in section in Fig. 6, and it consists of a box-shaped channel having bottom, front and rear walls which receive and guide the carrier chain. The upper side of the box is slotted at 14. Carrier posts 15 project from the chain up through the slot 14, and upon it may be carried things desired to be exhibited by the apparatus.

The carrier guide is held, in the illustrated embodiment, in a rectangular shape by means of four carrier chain pinions 16, one at each corner of the rectangle in which the carrier chain is formed. The carrier chain is driven by a sprocket gear 17. The carrier guide is provided with slots at its four corners through which the pinions project into the guide to engage the carrier chain. Similarly, the carrier guide is provided with a slot through which the carrier driving sprocket enters to engage and drive the carrier chain. The table is provided with a series of sockets 18 in which posts may be set to carry the devices or things for exhibition. The table may also be provided with a lamp carrier 19 for illuminating the apparatus.

The carrier posts 15 may be of any convenient number and arrangement, and are con-

veniently extensions of the pintles of the sprocket carrier chain 12. At 21 a shoe is shown carried by one of these posts 15.

In order to support and carry various devices on the display apparatus means are provided for driving different article carriers. Thus, the shaft upon which the carrier driving sprocket is supported may be provided, as shown in Fig. 6, with a rotating table 22. A second rotary element may be provided at 23, which is continuously rotated, being provided with a mitre gear, which is adapted to drive a mitre gear driven apparatus which may be set up on the table in proper relation to it. At 24 an oscillating shaft is provided which is adapted to be rotated first in one direction, and then in the opposite direction. This is intended also to carry an article to be exhibited, or a plate upon which an article may be carried, or otherwise.

In general, the support for the carrier driving sprocket produces a continuous slow rotary motion, the rotary element 23 is principally a take-off for conveying continuous rotary motion to a convenient nearby position, and the shaft 24 may be availed of for oscillating or reversed rotary motion. In addition, provision is made for driving the plate 22 above the carrier driving sprocket in such manner as to give it an intermittent rotary motion. One of the important features of the invention resides in the carrier guide which supports and holds the carrier in a certain position and guides it in its motion through a certain predetermined path so that an article carried by it will traverse a given path repeatedly. This carrier guide at all points except at the corners and at the place where the driving sprocket enters it to engage the chain, is rectangular in cross-section with a slot in the top through which a carrier post may project.

The mechanism for driving the carrier and for continuously rotating the mitre gear 23 and intermittently rotating the shaft at 24, is described as follows: The power is applied by means of a belt running to one of the pulleys 30, mounted on the shaft 31 of the gear box. Inside of the box the shaft 31 carries a worm 32, which engages a worm wheel 33 mounted on a second shaft 34 supported in bearings in the box and projecting at each end therefrom, so that other pulleys or gears may be applied to the ends of the shaft 34 so that continuous slow rotary movement may be imparted thereto from such shaft. This

shaft 34 carries a worm 35 which engages a worm wheel 36 having a hub 37 secured to the hollow shaft 38 by means of the set screw 40. This hollow shaft is provided with a hub 41 which carries the sprocket wheel 17 by which the carrier chain is driven. The shaft 34 also carries the worm 42 which engages the worm wheel 43, mounted on the shaft 44, supported in a bearing in the box and projecting out from the box, and adapted to receive a pulley or other device to be driven from the box. The worm 42 also engages the worm wheel 45, to which is secured the gear 46, both being mounted on the shaft 23 above referred to. 5 The gear 46 engages the gear 47 and rotates it continuously. This gear 47 is secured upon the shaft 48 carried by the box. The shaft 48 also carries a disk 50, carrying a pin 51 and a second disk 52. The pin 51 is adapted to 10 engage with the slots 53 of the Geneva wheel 54, which is permitted to turn when the disk 52 brings its cut away portion opposite one of the arms of the Geneva wheel 54, at which time the pin 51 operates to give the Geneva 15 wheel a step forward. The Geneva wheel 54 is mounted on the shaft 55, which passes through the center of the hollow shaft 38 and extends upwardly therethrough and beyond the end of the hollow shaft 38 at the top. 20 Here it is provided with a collar 56 secured to it, which rests upon the upper end of the hub 41 of the sprocket wheel 17. The upper end of the shaft 55 carries a sleeve 57, and on the outside of the sleeve the hub 58 of the disk 22 25 is adapted to fit. By loosening the screw 60 which passes through the hub 58 and tightening the screw 61, as shown in Fig. 6, the sleeve 57 will be attached to the sprocket wheel hub 41 and the table 22 will be continuously rotated from the sprocket wheel. 30 By loosening the screw 61, on the other hand, and tightening the screw 60, the table 22 will be secured to the intermittently rotated shaft 55, and the table 22 will thereby be given 35 an intermittent rotation. 40 Ordinarily, as has been described, the sprocket wheel 17 will be given a continuous rotary movement and thereby the carrier chain will be advanced continuously in the 45 operation of the apparatus. If desired, however, both of the screws 60 and 61 may be tightened and the screw 40 loosened, and then the sprocket wheel will be driven through the 50 shaft 55 by an intermittent or step by step 55 movement.

The hollow shaft 38 also carries a gear 62, the hub of which is secured to the hollow shaft 38 by the set screw 63. This gear 62 meshes with the gear 64, which in turn meshes with the gear 65, both of which are mounted 60 on bearings supported by shafts or studs carried by the box. One of these gears 65 carries a pin 66 which engages a slot 67 in the arm 68, which is pivoted on the stud which carries the gear 64. This arm 68 also carries a segmental gear 70, which meshes with the pinion 71 mounted on the shaft 24. By this means oscillating motion is imparted to the latter shaft. 65

The apparatus which forms the subject of 70 this invention is adapted for use in many different ways. Thus, the carrier chain may be advanced continuously, or it may be advanced step by step. The plate 22 mounted above the table may be rotated continuously, 75 or it may be rotated step by step. Also power may be taken off at 23 to drive other devices supported upon the table 10 for continuously rotating them, or power may be taken off from the shaft 24 for causing rotations to be 80 imparted to a device for exhibiting articles first in one direction, and then in the other. 85

Having thus described the invention, what is claimed is:

1. Display apparatus having, in combination, a support, a carrier guide mounted on the support consisting of a box-shaped channel having bottom, front and rear walls, a carrier chain received in the carrier guide, carrier chain pinions at corners of the carrier guide 90 for maintaining the latter in shape, the carrier guide being provided with slots at its corners through which the pinions project into it to engage the chain, and a carrier driving sprocket, the carrier guide being provided with a slot through which said sprocket enters to engage and drive the carrier chain. 95

2. Display apparatus having, in combination, a carrier chain having article-carrying posts secured to it projecting to one side of it, 100 a slotted carrier guide for holding the carrier chain in the desired shape and position, consisting of a box-shaped channel having bottom, front and rear walls which receive and guide the carrier chain, and carrier chain pinions at corners of the carrier guide for holding it in shape. 105

In testimony whereof I have signed my name to this specification.

FRANK L. PEABODY.
